UNITED STATES PATENT OFFICE.

JACOB W. ISBERG, OF WEST ALLIS, WISCONSIN.

ROPE-CLAMP.

1,026,587.

Specification of Letters Patent.

Patented May 14, 1912.

Application filed May 9, 1911. Serial No. 625,979.

To all whom it may concern:

Be it known that I, JACOB W. ISBERG, citizen of the United States, residing at West Allis, in the county of Milwaukee and State of Wisconsin, have invented new and useful Improvements in Rope-Clamps, of which the following is a specification.

The purpose of the present invention is the provision of means whereby a rope or 10 cord may be secured either by subjecting the same to tension or by releasing the same.

The invention consists essentially of a frame and a clamp adjustable in the frame by means of an inclined movement whereby 15 the rope, cord or like part may be secured so as to be held in the required adjusted position or automatically released to admit of the rope or like part moving freely.

In the specific construction the clamp consists of a frame comprising a base and side 20 members, the latter having slots which are arranged at an inclination to the base of the frame and a roller mounted in said slots and adapted to confine the rope, cord or like part, 25 said roller being controlled in its movements by proper manipulation of the rope so as to effect a clamping of the rope or an automatic release thereof.

The invention further consists of the 30 novel features, details of construction and combination of parts which hereinafter will be more particularly set forth, and illustrated in the accompanying drawings and finally claimed.

35 Referring to the drawings forming a part of the specification; Figure 1 is a front view of a rope clamp showing the relative position of the parts when the rope is made secure; Fig. 2 is a side view of the device; 40 Fig. 3 is a vertical central section.

Corresponding and like parts are referred to in the description and indicated in the several views of the drawings by the same reference characters.

45 The numeral 1 indicates the rope, cord or like part with which the invention is adapted to coöperate. The device comprises a frame which in transverse section is substantially of U-form and comprises a base 2 and side pieces 3. This frame may be constructed in any manner. The side pieces 3 have longitudinal slots 4 which are relatively inclined to the plane of the base 2. A hook 5 or like rope engaging device is formed upon 50 one of the side pieces 3 at a point above the inclined slot 4. When it is required to secure

the rope 1 or like part the same is drawn upward about the clamp device and over the hook or engaging device 5 and drawn downward with the result that the upward pull 60 upon the main portion of the rope or analogous part 1 causes the clamp device 6 to move in the inclined slots 4 and to clamp the part 1 between it and the base 2.

The clamp device 6 may be of any construction and preferably consists of a roller whose journals are mounted in the inclined slots 4. It is to be understood that the roller 6 and journals may be one part or may be separately formed.

In the operation of the invention the clamping device is placed upon the rope, cord or like part 1 with the latter passing between the base 2 and the roller or clamp device 6. Under normal conditions the rope 75 is adapted to play freely through the frame. To clamp the rope the end thereof is bent about the clamp device 6 and is passed over the hook or engaging device 5 and drawn upon with result that the clamp device 6 is 80 moved upwardly in the inclined slots 4 and caused to bind upon the rope and clamp the same between the base 2 and the member 6. To release the rope the same is disengaged 85 from the hook 5 and drawn downward thereby causing the clamp device 6 to move downward in the inclined slots 4, the latter by reason of their inclination causing the roller 6 to move away from the base 2 and releasing the rope which is adapted to move freely 90 through the frame. It is to be understood that the clamp device may be secured to any part to which the rope is adapted to be secured when moved to the required position.

The clamping device may be advantageously 95 used in connection with the rigging of vessels or with hoisting tackle generally or in any position requiring a rope or like part to be quickly secured and adapted to be instantly released.

From the foregoing description, taken in connection with the accompanying drawings, the advantages of the construction and of the method of operation will be readily apparent to those skilled in the art to which 105 the invention appertains, and while I have described the principle of operation of the invention, together with the device which I now consider to be the embodiment thereof, I desire to have it understood that the device 110 shown is merely illustrative, and that such changes may be made when desired as are

within the scope of the claim appended hereto.

Having thus described the invention, what is claimed as new is:

5 A rope clamp comprising a frame of substantially **U** form in cross section, said frame embodying a base and side pieces, the latter having slots arranged in a plane inclining to the plane of the base, one of the side pieces 10 having a hook at the end adjacent the end of the frame where the ends of the inclined slots are nearer the base for the rope to pass over, and a roller having journals at its ends

which are mounted in the inclined slots of the side pieces of the frame, said roller serving to clamp the rope against the base of the frame when the loose end of the rope is drawn upon after being passed over the said hook.

15 In testimony whereof I affix my signature 20 in presence of two witnesses.

JACOB W. ISBERG.
